WITNESS:

UNITED STATES PATENT OFFICE.

KENNETH H. FUNK, OF ELLSWORTH, KANSAS.

ROAD-MAKING MACHINE.

Application filed September 1, 1922. Serial No. 585,674.

To all whom it may concern:

Be it known that I, KENNETH H. FUNK, a citizen of the United States, residing at Ellsworth, in the county of Ellsworth and 5 State of Kansas, have invented new and useful Improvements in Road-Making Machines, of which the following is a specification.

This invention relates to a road working 10 machine, the general object of the invention being to provide means for providing a great range of adjustability for the parts and to so form the supporting frame and its wheel carrying parts that all side draft can 15 be overcome.

Another object of the invention is to so arrange the blades that there is no danger of the dirt piling up and stalling the machine as the dirt will readily slide off the 20 blades and be properly distributed by said blades.

This invention also consists in certain other features of construction and in the combination and arrangement of the several parts, to be hereinafter fully described, 25 illustrated in the accompanying drawings and specifically pointed out in the appended claim.

In describing my invention in detail, reference will be had to the accompanying 30 drawings wherein like characters denote like or corresponding parts throughout the several views, and in which:—

Figure 1 is a plan view of the invention.

Figure 2 is a side view.

Figure 3 is a rear view.

Figures 4 and 5 are sectional detail views of the hub of the circular frame and its associated parts.

Figure 6 is a detail view partly in section showing the means for connecting the 40 caster wheels with the circular frame.

Figures 7 and 8 are detail views showing the means for connecting the blades with 45 their supports.

In these views 1 indicates the main beam of the machine which is preferably constructed of a pair of channel members 2 which are spaced apart by blocks 3, the 50 parts being suitably connected together. This beam is connected at its rear end by the frame 4 with the rear axle 5, said frame being pivotally secured to the rear end by the bolt 6. A lever 7 is connected with the 55 frame so that the frame and axle can be rocked about the bolt 6 in order to over-

come side draft. The lever 7 is provided with the usual quadrant and pawl 8. The front end of the beam is connected with the frame 9 which supports the front axle 10. 60 11 indicates the front and rear wheels. A circular frame 12 has its hub 13 pivotally secured to the central block of the beam by the bolt 14 so that the frame 12 can be partly rotated on the beam. Caster wheels 65 15 are connected with the sides of the frame 12 and the frame 12 is held in adjusted position by means of pins 16 passing through bracket 17 on the beam and engaging any one of a number of holes 18 70 in the frame 12. A cross bar 19 is connected with the under part of the frame 12 by the uprights 20 and a chain or cable 21 has its ends connected with the cross piece, adjacent the end thereof, and this 75 chain or cable engages a drum 22 on the post 23 of the hand wheel 24 which is arranged at the front of the beam. Thus by rocking the post 23 by the hand wheel 24 the chain 21 can be caused to move the frame 80 12 through the bar 19. The blades are shown at 22', said blades being connected with the uprights 23' by the ball and socket connections 24' and the forked ends of these uprights are engaged by the levers 25 which 85 are pivoted to the channel member 26 which is supported on the frame 12. These levers 25 are provided with the usual quadrants and pawls 27. Thus by operating the levers 25 the blades can be raised and lowered. 90 The blades are also connected by the bars 28 with the cross bar 19, the two outside bars 28 having adjustable links 29 to change the lap of mold board or blade when shifting angle of blade to opposite side. The blades 95 or mold boards are preferably formed in two sections, the central one being longer than the end one.

A platform 30 is provided for the operator.

From the above it will be seen that the angle of the blades can be adjusted by moving the frame 12 through the hand wheel 24 and the parts associated therewith. They can also be adjusted vertically by means of 105 the levers 25. By moving the rear axle and its wheels by the lever 7, side draft of the machine is prevented and these parts also act to facilitate steering of the machine.

The beam 1 provides a long wheel base 110 and this is necessary to secure the great slant of the blades which is made possible by the

large circular frame 12. By placing the blades at a considerable slant the dirt with weeds and the like mixed therein will readily slide off the blades and be deposited 5 on the road so that there are no piles of dirt to be removed after the machine has passed over the road. This long wheel base also permits the rear wheels to be adjusted so that they act as a rudder to over come 10 all side draft. By the peculiar construction of this machine it will pass over ruts and holes without being affected thereby due to the circular frame being supported by the caster wheels and the long wheel base.

15 It is thought from the foregoing description that the advantages and novel features of my invention will be readily apparent.

I desire it to be understood that I may make changes in the construction and in 20 the combination and arrangement of the several parts, provided that such changes fall within the scope of the appended claim.

What I claim is:—

In a road scraping machine, a longitudinal beam, wheels supporting the beam, a 25

circular frame rotatably supported on the beam to rotate about a vertical axis, and provided with a series of aligned openings, an element insertible through any pair of the 30 openings in the rim of the frame to hold the beam against rotation, a pair of parallel beams extending across the frame and one of which being rigidly attached to the upper face of the frame, and the other being rigidly attached to the under face of the frame, 35 a road scraping blade arranged beneath the frame and extending parallel to the beams, a plurality of arms operatively connecting the scraper blade and that beam connected with the underface of the frame, 40 manually operable means connected with the last mentioned beam for rotating the frame, a platform carried by that beam supported upon the upper face of the frame, and a plurality of hand levers carried by 45 the platform and operatively connected with the scraper blade.

In testimony whereof I affix my signature.

KENNETH H. FUNK.
